OSCAR HOUGH, OF CAMROSE, ALBERTA, CANADA.

COLTER FOR PLOWS.

1,123,535.

Specification of Letters Patent.

Patented Jan. 5, 1915.

Application filed January 31, 1913. Serial No. 745,491.

To all whom it may concern:

Be it known that I, OSCAR HOUGH, of the town of Camrose, in the Province of Alberta, Dominion of Canada, have invented 5 certain new and useful Improvements in Colters for Plows, and do hereby declare that the following is a full, clear, and exact description of the invention, such as will enable others skilled in the art to which it ap- 10 pertains to make and use the same.

This invention relates to improvements in colters for plows and the objects of the invention are to provide certain improvements whereby the colter will be held firmly in position and in addition give support to the plow and will also serve to guide any roots or any other articles uprooted from the surface by the plow and it consists essentially 15 of the improved construction hereinafter de- 20 scribed in detail in the accompanying specification and drawings.

In the drawings, Figure 1 is a serial view showing the colter and the share and the landside elements of an improved form of 25 plow designed for use in connection therewith. Fig. 2 shows a cross section through the same when assembled. Fig. 3 is a perspective view of the assembled parts.

In the drawings like characters of reference indicate corresponding parts in all the 30 figures.

It may be stated that the improved form of colter herein described is adapted to be used particularly in connection with the 35 plow described in my application Serial Number 681,770.

Referring to the drawings, A represents the colter which is provided at its lower end with a flange 10. The share F is provided 40 with a lip or flange 28 formed integral therewith and bent beneath the point thereof in such a manner that it embraces the flange 10 of the colter A, the shoe 30 and the front end of the landside 31. This shoe 30 is preferably made angle-shaped in cross 45 section and is adapted to fit over the front end of the landside 31, which front is tapered off for that purpose.

The colter is characterized by having a 50 much greater slant than usually applied, the slant being substantially 30° and it is also provided with a laterally extending fin or projection 11 which is bent over and extends

laterally across the mold board and is adapted to form a guard element to protect the mold board from any roots or other obstructions which rise out of the ground. This projection is slightly inclined rearwardly so that obstacles encountering it will slide off rearwardly to one side. 55

As many changes could be made in the 60 above construction and many apparently widely different embodiments of my invention, within the scope of the claims, constructed without departing from the spirit or scope thereof, it is intended that all matter contained in the accompanying specification and drawings shall be interpreted as 65 illustrative and not in a limiting sense.

What I claim as my invention is:—

1. In a plow and in combination, a colter 70 having a flange on the bottom edge thereof, the cutting edge of the colter being disposed at an acute angle to the said bottom edge, a projecting fin bent over and extending laterally across the moldboard, and a share 75 having a flange formed integral therewith, substantially as described.

2. In a plow and in combination, a colter having a flange on the bottom edge thereof, the cutting edge of the said colter being disposed at an angle of substantially thirty degrees to the said bottom edge, a projecting fin bent over and extending laterally across the moldboard, a share having a flange 80 formed integral therewith, a shoe and a 85 landside, substantially as described.

3. In a plow and in combination, a colter having a flange on the bottom edge thereof, the cutting edge of the said colter being disposed at an angle of substantially thirty degrees to the said bottom edge, a projecting fin bent over and extending laterally across the moldboard, a share having a flange 90 formed integral therewith, such flange being bent beneath the point of the said share, a 95 shoe substantially angle shaped in cross section, and a landside substantially as described.

In witness whereof I have hereunto set my hand in the presence of two witnesses. 100

OSCAR HOUGH.
